CLAIM

The ornamental design for a device for reloading ink ribbon cartridges, as shown and described.

DESCRIPTION

FIG. 1 is a top plan view of a first embodiment thereof; FIG. 2 is a left side elevational view of the first embodiment of the device as shown in FIG. 1;

FIG. 3 is a right side elevational view of the first embodiment of the device as shown in FIG. 1;

FIG. 4 is a rear elevational view of the first embodiment of the device as shown in FIG. 5;

FIG. 5 is a bottom plan view of the first embodiment of the device;

FIG. 6 is a front elevational view of the first embodiment of the device as shown in FIG. 5; and,

FIG. 7 is a top plan view of a second embodiment thereof; and

other views of the second embodiment would be identical to FIGS. 2 through 6.

The names IIMAK and DURACOAT forming part of the claimed design are registered trademarks of International Imaging Materials Inc.
